(57) **CLAIM**

The ornamental design for a stand for terminal equipment as shown and described.

DESCRIPTION

FIG. 1 is a perspective view of a stand for terminal equipment showing my new design in a first alternate position, showing the stand for terminal equipment in a folded state; FIG. 2 is a perspective view of the stand for terminal equipment of FIG. 1 in a second alternate position, showing the stand for terminal equipment in an unfolded state; FIG. 3 is a front view of the stand for terminal equipment of FIG. 1;

FIG. 4 is a rear view of the stand for terminal equipment of FIG. 1;

FIG. 5 is a left view of the stand for terminal equipment of FIG. 1;

FIG. 6 is a right view of the stand for terminal equipment of FIG. 1;

FIG. 7 is a top view of the stand for terminal equipment of FIG. 1; and,

FIG. 8 is a bottom view of the stand for terminal equipment of FIG. 1.
